Primary Examiner — Lakiya G Rogers*Assistant Examiner* — Julice Seung Eun Oum(74) *Attorney, Agent, or Firm* — Rankin, Hill & Clark LLP(57) **CLAIM**

The ornamental design for a fitness weight handle, as shown and described.

DESCRIPTION

FIG. 1 is a top front right side isometric view of a fitness weight handle showing my new design;

FIG. 2 is a bottom rear left side isometric view of FIG. 1;

FIG. 3 is a front elevation view of FIG. 1;

FIG. 4 is a rear elevation view of FIG. 1;

FIG. 5 is a left side elevation view of FIG. 1;

FIG. 6 is a right side elevation view of FIG. 1;

FIG. 7 is a top plan view of FIG. 1; and,

FIG. 8 is a bottom plan view of FIG. 1.

The broken lines in the drawings depict portions of the fitness weight handle that form no part of the claimed design.

1 Claim, 6 Drawing Sheets(56)
